UNITED STATES PATENT OFFICE

ISAAC C. DECKER, OF MONTGOMERY, PENNSYLVANIA

CHAIR

Application filed November 22, 1928. Serial No. 321,244.

This invention relates to chairs and especially to those of the adjustable or reclining type.

The primary object of the invention is the provision of a chair of this type having an adjustable seat and an adjustable back, so interconnected that a person occupying the chair may effect adjustment of these parts readily to accommodate his particular desires by simply altering the position of his body in the chair.

It is intended that the adjustable parts have a range of movement from a sitting position to a full lounging or reclining position, with provision for the automatic maintenance of the parts in full reclining position or in any position intermediate the full reclining and sitting positions to which they may be moved by the occupant.

20 It is also intended that the chair seat and back be so arranged as to return automatically to their normal sitting position immediately upon an occupant removing his body from the chair.

25 A further object is the designing of improved and simplified means for operating the interconnected back and seat, whereby the weight of the occupant serves to automatically maintain the parts in adjusted position.

30 Provision for ready disassembly of certain of the parts of the chair to facilitate shipping is also an object of the invention. Further objects will appear from the detailed description given hereinafter.

35 Reference is now had to the accompanying drawings, wherein there is shown a practical embodiment of the invention and in which:

Fig. 1 is a plan view of the preferred form 40 of my improved chair with the parts in their normal or sitting position and the chair seat removed to show the underlying parts;

Fig. 2, a side elevational view of the chair seat;

45 Fig. 3, a transverse section taken on line 3—3 of Fig. 2;

Fig. 4, a longitudinal sectional view taken on line 4—4 of Fig. 1, with the parts in normal or sitting position and the chair seat 50 in place;

Fig. 5, a similar view with the parts shown in their full lounging or reclining position;

Fig. 6, a fragmentary perspective view of one of the lower corners of the chair back and its connection with one of the seat operating 55 mechanisms.

Fig. 7, a sectional view, similar to Fig. 4, of a modified form of the invention with the parts in normal or sitting position; and

Fig. 8, a sectional view, similar to Fig. 5, 60 of the same modification, with the parts in full reclining or lounging position.

The chair comprises a base or frame 1 having the usual legs 2 and arms 3. Chair frame 1 comprises side boards 4, 5, and end boards 65 6, 7, which are firmly secured together at their extremities to furnish a rigid framework to support the other parts of the chair proper and the mechanism which provides for relative adjustment of the seat and back 70 of the chair.

Mounted on the inner faces of the side boards 4, 5 of the chair frame are the devices whereby the chair back 8 is pivotally mounted on the frame 1 and is interconnected 75 with the chair seat 9, so as to provide for the desired relative movement of the back and seat. Inasmuch as this mechanism is duplicated on each side of the chair frame 1, only one of the devices will be described in detail. 80

Each of these devices comprises an elongated metal plate 10, which is suitably secured, as by means of screws 11 or the like, to side board 4. At its rear end plate 10 has an upwardly projecting extension 12 in the upper portion of which the chair back 8 is 85 adapted to be pivotally mounted as will be described more particularly hereinafter.

Pivotally mounted on the inner face of plate 10, intermediate the ends thereof and on a rivet 13 extending through the two members, is a camming plate or member 14. The active or camming edge portion of plate 14, as appears clearly in Figs. 4 and 5, is formed with an integral inwardly projecting curved flange 15. The disposition of flange 15 with reference to the rivet 13 on which plate 14 is adapted to swing is such that the forward end of flange 15, as shown in Fig. 4, is appreciably closer to rivet 13 than is the op- 100

posite end thereof. The purpose of this will be explained later.

Connecting a pin or stud 16 provided in the forward end of plate 10, and a stud 17 provided on the outer face of camming plate 14, above rivet 13, is a heavy coil spring 18.

A link 19 is pivotally connected at its forward end by means of a rivet 20 to the lower extremity of camming plate 14. At its opposite end link 19 is pivotally connected by means of a rivet 21 to a perforated ear 22 on the lower end of a socket 23 secured to the lower portion of the chair back 8.

Chair back 8 comprises upholstery 8' and is formed on a wooden frame which includes side members 24, 25 and bottom member 26 which connects the side members together. As shown in Fig. 6, socket 23, which is preferably made of sheet metal, is tapered downwardly and inwardly, and in order that side members 24, 25 of the framework of the back may be received in the sockets, the side members are tapered correspondingly at their lower extremities. Tongues 27, 28 are provided on each of the back-carrying sockets 23 and are perforated to receive suitable fastening means, such as screws, whereby the back 8 is firmly secured in the sockets.

Each socket 23 is pivotally mounted on the extension 12 formed on plate 10. For this purpose the upper portions of these members are provided with suitable registering openings through which extends a rivet or pin 29 which thus forms the pivotal connection between the members.

With the arrangement above described, it will be evident that coil springs 18, 18, being put in place under tension, normally serve to maintain camming plates 14, 14 in the position shown in Fig. 4. As a result of this, the lower extremities of the chair back 8 will be forced rearwardly by means of links 19, 19, against end board 7, thereby holding the upper portion of the chair back in its normal sitting position.

As shown in Fig. 5, when the upper portion of the chair back 8 is swung backwardly about rivets or pivot pins 29, 29 towards the lounging or reclining position, links 19, 19 are forced forwardly. This results in camming plates 14, 14 being rotated in a clockwise direction about their pivots 13, 13 against the gradually increasing tension of coil springs 18, 18, which latter always tend to return the parts to the normal position of Fig. 4.

The chair seat 9, which comprises a frame 30 and upholstery 31, is also pivotally mounted in the chair frame 1. The pivotal connection between the chair seat and frame is located at the forward portion of the chair and comprises a small metal plate 32, suitably secured to the forward portion of each of the side boards 33, 34 of seat frame 30. Each plate 32 is provided at its forward end

with a downwardly and rearwardly inclined slot 35 which is open at its lower end to receive a headed stud or pivot pin 36 rigidly mounted on the inner face of the side board of the chair frame 1, as appears clearly in Fig. 1. Clearance is provided under plate 32 for the free reception of the head of stud 36.

The upper portion of each of the side boards 33, 34 of the seat frame is increased in thickness so as to provide a horizontal ledge or shoulder 37. As is shown in Fig. 4, when the seat 9 is in place on its pivot pins 36, 36, the curved edges 15, 15 of camming members 14, 14 engage ledges or shoulders 37, 37 and thus support the rear portion of the seat. With the seat in the position shown in this figure, it will be evident that, by reason of the inclination of the slots 35, 35 in plates 32, 32, the seat cannot be removed by lifting it bodily. It is necessary to swing the seat upwardly about its pivots 36, 36 until the operator can grasp both the front and rear edges of the seat, when it may be pulled forwardly and upwardly off of the pivot pins.

To replace the seat, the reverse of this operation is performed, that is, the front of the seat 9 is first placed on its pivot pins 36, 36 with the rear portion of the seat held in an elevated position. As soon as the pivotal connection is completed, the rear portion of the seat is lowered into place on camming members 14, 14. The seat is then secured in place and may only be removed by the procedure just outlined.

In order to secure the desired coaction between each ledge 37 and the curved flange 15 of the corresponding camming member 14, ledge 37 is formed with an upwardly extending curved portion or recess 38 and an adjoining downwardly extending curved portion or protuberance 39. As shown clearly in Fig. 4, curved portions 38 and 39 gradually merge into each other, so as to provide a continuous operating surface.

Normally, that is in the upright or sitting position, the rear ends 40, 40 of camming flanges 15, 15 are in contact with the uppermost portions of curved surfaces or recesses 38, 38, being held in this position by coil springs 18, 18. When the chair is occupied, the parts are further maintained in this position by the weight of the occupant on the chair seat 9. The resulting downward pressure on the rear portion of the seat creates a frictional resistance between curved portion 38 and the rear edge 40 of flange 15 to the tendency of camming member 14 to move in a clockwise direction as a result of any pressure exerted against the chair back by the occupant. In order to further insure the maintenance of the seat and back in normal sitting position, unless more than ordinary pressure is exerted by the occupant against the chair back to move it towards reclining position, curved portion 38 and protuberance 39

39 are so formed that the distance between pivot pin 13 of camming member 14 and the uppermost portion of curved surface 38 is greater than the distance between pivot 13 and the lowermost portion of protuberance 39. As a result of this, there is an initial relatively high resistance to the movement of the several parts from the sitting position, but as soon as rear edge 40 of camming flange 15 reaches the lowermost point of protuberance 39, this resistance is overcome and protuberance 39 rides on camming flange 15 as shown in Fig. 5.

Thus, the occupant of the chair need not hold himself in a strained position in order to prevent the back of the chair from swinging downwardly into a reclining position, but may occupy the chair in a natural manner and still remain in the sitting position. When it is desired to move to a reclining position, a slight pressure of the occupant's back against the back of the chair and a consequent slight raising of his body from the seat of the chair will result in the desired change in the position of the back and seat.

After the protuberance 39 has come into contact with the outer surface of camming flange 15, the occupant of the chair will still have full control over the relative angular relation of the seat and back due to the frictional resistance to the continued movement of the parts caused by the contact of protuberance 39 on flange 15 and the weight of the occupant's body on the seat. Slight pressure by the occupant upon the chair back 8 will result in movement of the parts to any desired position and the frictional resistance just mentioned will maintain the parts as adjusted, thereby relieving the occupant of any strain or effort to hold the parts in place.

It will be evident that as the chair back 8 is swung rearwardly toward the full reclining position, a gradual lowering of the rear portion of chair seat 9 will result due to the contour of the camming edge or flange 15. This is accomplished without any change in the height of the front portion of the seat and thus serves to adjust the body supporting portions of the chair so as to render them most comfortable.

Referring to Fig. 5, which shows the parts in full reclining position, it will be seen that movement beyond this position is prevented by the engagement of rear edge 40 of flange 15 with the upper edge of link 19. The lower outer edge 41 of the chair back at the same time engages with the upper edge of the end board 7 of the chair frame and thus also serves to limit the movement.

In the full reclining position, it will be seen that the forward end 42 of flange 15 is in contact with the lowermost portion of protuberance 39 and, consequently, the rear portion of seat 9 is in its lowermost position. As soon as the occupant removes his body

from the chair, coil springs 18, 18 return the parts to the normal sitting position of Fig. 4 with the rear portion of the seat in its highest position. This movement is readily accomplished by the springs when the chair seat is relieved of the weight of the occupant's body, and the considerable friction caused thereby in the operating mechanism is eliminated.

The construction of the modified form of the invention is illustrated in Figs. 7 and 8 and is to a large degree the same as that of the form shown in Figs. 1-6, inclusive. The main difference, as shown in Fig. 7, is that the operative connections between the chair back 8 and the seat 9 are arranged so that in the sitting position the rear portion of the seat is at its lowest level instead of at its highest level, as in the preferred form. Consequently, in the modified form the rear portion of the seat is at its highest level when the parts are in the full reclining position, as shown in Fig. 8.

In order to accomplish the movements of the back and seat just described, the connections of each coil spring 18 and each link 19 to the corresponding camming plate 14 are reversed. That is, spring 18 is connected to plate 14 by means of pin 20 instead of pin 17, and link 19 is connected to the plate by pin 17 instead of pin or rivet 20.

With this arrangement, in the normal or sitting position of the parts, as appears from Fig. 7, the rear end 40 of camming flange 15 is in engagement with the lowermost point of protuberance 39. Since the distance between end 42 of flange 15 and the pivot 13 of plate 14 is less than the distance between this pivot and any other part of flange 15, the rear portion of seat 9 is now in its lowermost position. The parts, as before, are held in this position by springs 18, 18.

Rearward movement of the chair back 8 towards the full reclining position, as shown in Fig. 8, will result in links 19, 19 rotating camming plates 14, 14 in a counter-clockwise direction on their pivots against the resistance of springs 18, 18. As this movement continues, the rear portion of chair seat 9 will gradually be raised by camming flanges 15, 15 from its lowermost position of Fig. 7 to its highest or full reclining position as shown in Fig. 8. Further movement of the parts in this direction is prevented by engagement of links 19, 19 with the projecting heads of pivot pins 13, 13 and the lower outer edge 41 of the chair back with the top of end plate 7 of the frame.

With the parts in full reclining position, the relation between camming flange 15 and the curved surfaces 38, 39 is the same as it was in the arrangement shown in Fig. 4. In other words, the shape of these surfaces is such that a relatively high initial resistance to the movement of the parts from the full

reclining position is established. The resistance tends to maintain the parts in this extreme position, as it similarly tends to maintain the parts in the opposite extreme or sitting position in the preferred form of the invention, as appears from Fig. 4.

In both forms of the invention, it will be clear that the occupant, without moving from the chair, can move the parts to any desired position upon applying slight pressure on the back, and the parts will remain in the adjusted position as long as he occupies the chair.

Various changes may be made in the details of construction of the device, since it is not intended that the invention be restricted to the construction shown, except as it may be limited by the appended claims.

What is claimed is:

20. 1. In a chair, the combination of a frame; a back swingably mounted intermediate its ends in the frame; a seat pivotally supported in the frame independently of the back, said seat and back being adapted for movement relative to each other; and means interposed between the back and the seat for effecting a lowering of the rear portion of the seat upon rearward swinging movement of the back.
25. 2. In a chair, the combination of a frame; a seat pivotally mounted at its forward edge for vertical swinging movement in the frame; a back mounted for swinging movement in said frame; operative connections between the back and seat for effecting a downward swinging movement of the seat upon rearward swinging movement of the back and an upward swinging movement of the seat upon forward swinging movement of the back, said operative connections all being located entirely below the upper surface of the seat.
30. 3. The combination in a chair of a frame; a pair of tapered sockets pivotally mounted on said frame; and a back rigidly mounted in said sockets for movement therewith relative to the frame.
35. 4. In a chair, the combination of a frame; an adjustable seat mounted in the frame; a pair of tapered sockets pivotally mounted on said frame; a back rigidly mounted in said sockets for movement therewith relative to the frame; and operative connections interposed between said sockets and the seat for effecting movement of the seat when the back is moved.
40. 5. The combination in a chair of a frame; a seat pivotally mounted at its front edge in the frame; a back pivotally mounted in the frame; and cam means, on said frame, supporting the rear portion of the seat, said back and said cam means being operatively connected, so as to effect a swinging movement of the seat upon movement of the back.
45. 6. In a chair, the combination of a frame; a seat pivotally mounted in the frame, said seat being provided on its sides with ledges

having adjoining upwardly and downwardly curved surfaces; a back pivotally mounted on the frame; cams pivoted on the frame and engaging said ledges on the seat; and operative connections between the back and said cams for causing the cams to coact with said adjoining curved surfaces upon movement of the back and effect swinging movement of the seat.

7. An operating mechanism adapted to be interposed between the adjustable seat and back of a chair to effect movement of the seat when the back is moved, comprising a supporting member; a cam pivotally mounted on said member intermediate its ends; a spring connected at one end to the cam on one side of its pivot and at its opposite end to the supporting member; a link connected at one end to the cam on the opposite side of its pivot; and back-carrying means operatively connected to the other end of said link and pivotally mounted on said supporting member.

8. An operating mechanism adapted to be interposed between the adjustable seat and back of a chair to effect movement of the seat when the back is moved, comprising an elongated supporting member; a cam pivotally mounted thereon; a spring connected to the supporting member at one end and at its opposite end to the cam on one side of the pivot thereof; a link connected at one end to the cam on the opposite side of its pivot; a socket pivotally connected to the other end of said link; and a pivotal connection between said socket and the supporting member.

9. In a chair, the combination of a frame; a seat pivotally mounted at its forward edge in the frame and having overhanging ledges on its sides to the rear of said pivot; a back pivotally mounted near its lower end in the frame; and operating means mounted on the frame and connected to the chair back below its pivot, said operating means including a pair of pivoted cams having body portions located between the seat and the chair frame and provided with peripheral flanges upon which said overhanging seat ledges rest at all times and connections between the back and said body portions on the flange sides of the cams, whereby rearward swinging movement of the upper portion of the chair back results in downward swinging movement of the rear portion of the seat.

In testimony whereof I have signed my name to this specification.

ISAAC C. DECKER.

CERTIFICATE OF CORRECTION.

Patent No. 1,846,795.

Granted February 23, 1932, to

ISAAC C. DECKER.

It is hereby certified that error appears in the printed specification of the above numbered patent requiring correction as follows: Page 4, line 42, claim 3, strike out the word "tapered"; and that the said Letters Patent should be read with this correction therein that the same may conform to the record of the case in the Patent Office.

Signed and sealed this 5th day of April, A. D. 1932.

**M. J. Moore,
